(57) **CLAIM**

The ornamental design for a heated apparel controller, as shown and described.

DESCRIPTION

FIG. 1 is a front perspective view of a heated apparel controller, showing my new design;

FIG. 2 is a front elevational view thereof;

FIG. 3 is a rear elevational view thereof;

FIG. 4 is a left side view thereof, the right side view being a mirror image of FIG. 4; and,

FIG. 5 is a top plan view thereof, the bottom plan view being a mirror image of FIG. 5.

The dashed broken lines in the figures are for the purposes of illustrating portions of the heated apparel controller, which form no part of the claimed design.

The dash-dot-dot broken lines in the figures are for the purposes of illustrating unclaimed boundaries which form no part of the claimed design.
